UNITED STATES PATENT OFFICE.

JOE MACHOWSKI, OF BUFFALO, NEW YORK.

SAFETY POUCH.

Application filed February 9, 1923. Serial No. 618,112.

To all whom it may concern:

Be it known that I, JOE MACHOWSKI, a citizen of the Republic of Poland, residing at Buffalo, in the county of Erie and State 5 of New York, have invented new and useful Improvements in Safety Pouches, of which the following is a specification.

This invention relates to fastening devices for receptacles, such as bags, mail 10 pouches and the like and has for an object the provision of a simple and reliable means for closing the mouth of a bag or pouch to prevent its accidental or unauthorized opening.

Another object of the invention is the provision of a fastening device of this character which may be operated without the use of a key, the invention being such that only persons familiar with the device may 15 operate the same.

With the above and other objects in view, the invention further includes the following novel features and details of construction, to be hereinafter more fully described, illus- 20 trated in the accompanying drawings and pointed out in the appended claims.

In the drawings:—

Figure 1 is a perspective view of a pouch with the fastening device shown closed.

Figure 2 is a similar view with the parts arranged just prior to releasing.

Figure 3 is a like view showing the fastening device in open position.

Figure 4 is an enlarged transverse sectional view with the parts in the position shown in Figure 1.

Figure 5 is a section at right angles to Figure 4.

Figure 6 is a detail perspective view of the 40 fastening member.

Referring in detail to the drawings, wherein like characters of reference denote corresponding parts, the reference character 10 indicates a mail pouch, whose opening or mouth is provided with spaced oppositely disposed slots 11 for the passage of rings 12, which are preferably formed of metal. These rings are designed to pass through opposite slots for the purpose of closing the 45 mouth of the pouch.

In order to hold the rings in closed position, there is provided a flexible member 13 which passes through the rings 12 on one side of the pouch and through openings 14 50 adjacent each side edge. One end of the

flexible member 13 passes through a slot 15 provided in a fastening member 16, the latter extending through the rings 12 upon the opposite side of the pouch. The fastening member 16 may be formed of flexible 60 material and is provided at one end with an eye 17 through which the opposite end of the flexible member 13 is passed, so that the said flexible member will be passed through the opposite ends of the fastening 65 member 16 beyond the outer rings 12 and will prevent said fastening member 16 from being drawn through the rings so that the mouth of the pouch will be held in closed 70 position. One end of the flexible member 13 has secured thereto a ring 18, through which the opposite end of the flexible member is passed and this last mentioned end has secured thereto a ring 18^a which is similar 75 in shape and size to the ring 18 so as to prevent its passage therethrough. A closed loop is thus formed, whose ends are permanently and slidably connected, so that the fastening member 16 is held in position within the rings 12 to prevent the opening of the mouth 80 of the pouch.

In order to open the pouch, the ring 18 is passed over the slotted end of the fastening member 16 and the end of the flexible member carrying the ring 18^a is drawn 85 through the slot 15 in the manner indicated in Figure 2 of the drawings, whereupon the ring 18 may be removed from the end of the member 16 and the latter withdrawn from the rings 12. The rings may then be passed 90 through the slots 11 and the mouth of the pouch opened.

To fasten the pouch, the rings are again inserted in the slots 14 and the member 16 passed through the rings. The ring 18 is 95 again passed over the slotted end of the member 16 and the ring 18^a drawn through said slot, after which the ring 18 is removed from the member 16 and the pouch again fastened as shown in Figure 1 of the 100 drawings.

The invention is susceptible of various changes in its form, proportions and minor details of construction and the right is herein reserved to make such changes as properly fall within the scope of the appended 105 claims.

Having described the invention what is claimed is:—

1. A fastening device for pouches embody- 110

- ing a plurality of rings adapted to extend transversely across the mouth of the pouch through slots provided in the opposite sides of said pouch, said pouch being also provided with spaced registering openings, a flexible member extending through the rings upon one side of the pouch and having its opposite ends extending through the registering openings, a slotted fastening element 5 adapted to extend through the rings upon opposite sides of the pouch to prevent removal of the rings and hold the mouth of the pouch closed, means permanently connecting the ends of the flexible member and 10 means whereby the flexible member may be detachably engaged through and disengaged from the slotted fastening element.
2. A fastening device for pouches embodying a plurality of rings adapted to extend transversely across the mouth of the pouch through slots provided in the opposite sides of said pouch, said pouch being also provided with spaced registering openings, a flexible member extending through the 15 rings upon one side of the pouch and having its opposite ends extending through the registering openings, a slotted fastening element adapted to extend through the rings upon the opposite side of the pouch and receive the flexible member and means slidingly and permanently connecting the ends of the flexible member.
- 16 ing its opposite ends extending through the registering openings and permanently and slidingly connected to form a closed loop and a slotted fastening member extending through the rings upon the opposite sides of the pouch and adapted to receive the flexible member in a manner to removably include the slotted fastening member in the loop.
3. A fastening device for pouches embodying a plurality of rings adapted to extend transversely across the mouth of the pouch through slots provided in the opposite sides of said pouch, said pouch being also provided with spaced registering openings, a flexible member extending through the 20 rings upon one side of the pouch and having its opposite ends extending through the registering openings, a slotted fastening element adapted to extend through the rings upon the opposite side of the pouch and receive the flexible member and means slidingly and permanently connecting the ends of the flexible member.
- 25

In testimony whereof I affix my signature.

JOE MACHOWSKI.
